UNITED STATES PATENT OFFICE.

GEORGE J. MEYER, OF MILWAUKEE, WISCONSIN.

SAFETY ATTACHMENT FOR ELEVATORS.

1,386,194.

Specification of Letters Patent. Patented Aug. 2, 1921.

Application filed August 5, 1919. Serial No. 315,510.

To all whom it may concern:

Be it known that I, GEORGE J. MEYER, a citizen of the United States, residing at Milwaukee, county of Milwaukee, and State of Wisconsin, have invented new and useful Improvements in Safety Attachments for Elevators, of which the following is a specification.

My invention relates to improvements in safety attachments for elevators.

The primary object of my invention is to provide means whereby doors at the respective landings of an elevator well or shaft may be utilized to lock the car at any given landing, and to simultaneously lock the controller lever when the car has stopped at the landing and the door has been opened.

A further object of my invention is to provide means whereby an insecurely latched door will be prevented from opening after the car has left the landing, and whereby the operator of the car will be notified immediately in case any door is unlatched while the car is in motion.

25 In the drawings:—

Figure 1 is a vertical sectional view of a portion of an elevator shaft or well, drawn to a plane which intersects the car, and exposes the wall provided with the controlling lever and exit.

Fig. 2 is a sectional view of the upper portion of the well, as shown in Fig. 1, drawn on line 2—2 of Fig. 1.

Fig. 3 is a cross sectional view, drawn on line 3—3 of Fig. 1.

Fig. 4 is an end view of the oscillatory member for locking the controlling lever, with dotted lines indicating said member in locking position, a fragment of the car wall being also illustrated.

Like parts are identified by the same reference characters throughout the several views.

The elevator cage or car 1 is actuated by one or more cables 2 along guide posts 3 of the well in the ordinary manner, the car being provided with a controlling lever 4 of ordinary type. The well is provided with walls, or with landing cages 5 at the various floors 6, and each of these cages or sets of inclosing walls is provided with a door 7, which is preferably suspended from the walls 5 or any other suitable overhead support by parallel links 8 pivotally connected with the door near the respective sides thereof, as indicated at 9, and also pivoted to the

overhead support at 10. These links are obliquely disposed or inclined from a vertical position when the door is closed, and also when it is in full open position, whereby the door may swing with a pendulum motion, its lower margin being guided in a slot 11 formed in the floor 6. This means for supporting and guiding the door is made the subject of a separate application bearing even date herewith, and is not claimed herein. It is referred to merely for the purpose of explaining the means for notifying the operator of an unlatched door, as hereinafter described.

Brackets or shouldered projections 14 and 15 are secured to the outer side of the wall 16 of the car, this being the wall provided with an exit 17, which registers with the doors 7 at the respective landings when the car is brought to a stop at such landings. Each of the doors 7 is provided with a curved bar 18 secured to the inner face of the door in a position to pass between the projections 14 and 15 when the car is in proper position, and the door is being opened. Therefore, when the door has been opened, the bar 18 locks the car to the door in such a manner that the car cannot be moved vertically in either direction without either tearing away the door or breaking the bar 18 from the door. To prevent such an accident, I provide auxiliary means for locking the controller lever in neutral position, which will now be described.

The inner face of the wall 16 of the car is provided with an oscillatory shaft 20 connected with the wall by suitable bearing brackets 21 in which the shaft may oscillate. One end of the shaft is in proximity to the exit 17, and is provided with an elbowed arm 22, which extends through a slot in the wall into the path of the bar 18, the latter being tapered or rounded at 23, whereby when the car is positioned at a landing, and the door opened, the bar 18 will strike the outwardly projecting end of arm 22, and push it toward the interior of the car, thereby oscillating shaft 20. Shaft 20 is provided with a set of arms 25 and 26 which normally project upwardly from the shaft, but which are adapted to swing toward the interior of the car, and to receive controlling lever 4 between them when said lever is in the vertical or neutral position, as illustrated in Fig. 1. Therefore, when these arms 25 and 26 are swung downwardly by the oscillating

shaft 20 they will necessarily project across the path of the controller lever 4 on each side thereof, and prevent the lever from being swung in either direction from neutral position. Inasmuch as it will be necessary to bring the lever to neutral position in order to bring the car to rest at the landing, it is obvious that by opening the door the controller lever is locked and the car is also locked to the door by the operation of the bar 18.

Any ordinary door latches 30 and 31 may be employed to fasten the door 7 in its respective full open or closed positions. When 15 fully closed, bar 18 will, of course, be retracted not only from its locking position between the brackets or projections 14 and 15 on the outer face of the car wall, but it will also be retracted from the arm 22. As 20 it is retracted from this arm, the shaft 20 will return to normal position under the tension of the retracting spring 33.

If the door 7 should be insecurely latched in closed position, it will, of course, tend to 25 swing toward open position immediately, and thus prevent the car from starting by locking the controlling lever, and also locking the car to the door, as above explained. But if it should be held by the operator, or 30 by an insecurely engaged latch in closed position until the car has moved away from the landing, it would, of course, tend to swing toward open position when released. To avoid injuries which might result in such 35 case, I preferably connect the ends of a cable 35 to the brackets 14 and 15, and extend this cable around pulleys 36 and 37 at the top and bottom of the well. This cable operates as an endless cable, since the brackets 40 14 and 15 and the wall of the car form a means of connection between its ends. The cable is so disposed that it crosses the paths of the bars 18 of all the doors at the various landings in the series, except the door 45 at a landing where the car is positioned. Therefore, if a door becomes unlatched or released after the car has left the landing, a short initial movement toward open position will bring its associated bar 18 into 50 contact with the cable. If the car is in motion, the cable will, of course, draw across the end of the bar in rubbing frictional contact therewith. The vibrations will be transmitted to the car through the cable and 55 to the door through the bar 18, and the noise will instantly advise the operator that a door has opened. The cable will in the meantime prevent the door from opening far enough to allow any person on the associated landing to accidentally step from the landing into the well, but the car may be 60 operated and thereby brought to such landing, and the door properly closed by the operator before proceeding on his way.

65 It will be understood that my invention is

applicable to any form of elevator mechanism, and any form of door or door supporting devices may be employed at the respective landings, but the particular means for suspending the door as illustrated herein 70 is preferred for the reason that an unlatched door will immediately tend to swing toward open position, and will therefore give immediate notice of the fact that it is unlatched in case the car is not at rest. 75

I claim:—

1. The combination with a landing door and car of an elevator mechanism, of a locking device secured to the door and adapted 80 for interlocking engagement with the car when the door is open.

2. The combination with a landing door and car of an elevator system, of means for interlocking the door with the car when the car is in registry with the landing and the 85 door is moved toward open position.

3. In an elevator mechanism, a landing door, and a flange carried by the door and adapted when the door is opened to interlock 90 with portions of an elevator car.

4. In an elevator mechanism, a landing door adapted, when opened, to move into interlocking engagement with the car, in combination with a car having a controlling lever, and locking devices for said lever, adapted to be actuated to locking position by the door. 95

5. In an elevator mechanism, a landing door adapted, when opened, to move into interlocking engagement with the car, in 100 combination with a car having a controlling lever, and locking devices for said lever, adapted to be actuated to locking position by the door, and to automatically release the controlling lever when the door is closed. 105

6. The combination with the walls and landings of an elevator well, of a car adapted to travel in said well, and provided with actuating mechanism, doors at the respective landings controlling admission to and exit 110 from the well, and a cable extending over pulleys at the top and bottom of the well, and connected with the car, said pulleys being adapted to support the cable in a position to limit the opening movement of each of the doors, except when the car is positioned at such door. 115

7. The combination with the walls and landings of an elevator well, of a car adapted to travel in said well, and provided with actuating mechanism, doors at the respective landings controlling admission to and exit from the well, and a cable extending over pulleys at the top and bottom of the well, and connected with the car, said pulleys being adapted to support the cable in a position to limit the opening movement of each of the doors, except when the car is positioned at such door, and means connected 120 with the door for locking the car against 125 130

vertical movement when the door has been opened to permit entrance to or exit from the car.

8. In an elevator mechanism, the combination with a car and a set of relatively stationary landing doors, of a traveling member connected to, and movable with the car, and adapted to hold distant doors in a substantially closed position.

10 9. In an elevator mechanism, the combination with a car and a series of relatively stationary landing doors, of a car actuated door retaining device in continuous door stop relation to all doors in the series

15 when the car is out of registry therewith.

10 10. In an elevator mechanism, the combination with a car and a set of relatively stationary landing doors, of a door controlling member connected to travel vertically with the car and adapted to hold all doors in substantially closed position when the car is out of registry therewith.

11. In an elevator mechanism, the combination with an elevator well and a car movable therein, of a moving door stop adapted to travel longitudinally along the line of car movement in correspondence with the movement of the car, and operative to hold all doors in substantially closed position, when the car is out of registry therewith.

12. In an elevator mechanism, the combination with a car and a landing, of a pendulous landing door, spaced apart projections carried by the car, and a curved flange carried by the door and adapted to pass freely between said projections to an

interlocking position when the car is in registry with the landing.

13. In an elevator mechanism, a car, a plurality of landings, doors at said landings, a locking member carried by each door, and an interacting locking device carried by the car adapted to secure all doors against movement except that of the landing with which the car is in registry, and to interlock with the locking member of the particular door it allows to open.

14. In an elevator mechanism the combination with a car provided with a controlling lever, of locking devices for said lever, a spring normally holding the locking devices out of lever engaging position, and landing doors, each provided with a controlling member adapted, when the door is opened, to swing the locking devices to locking position with a car at such landing and to move into interlocking relation with said car.

15. The combination with a landing door and car, of an elevator system, of interlocking members connected with the door and car respectively and adapted to allow the door to move freely into interlocking relation to the car when the door is opened and the car is in correct position of adjustment without added resistance due to the interlocking members.

In testimony whereof I affix my signature in the presence of two witnesses.

GEORGE J. MEYER.
